C. T. DEAN,
INK SAVING ATTACHMENT FOR EMBOSsing PRESSES.
APPLICATION FILED MAR. 25, 1915.

1,252,409.

Patented Jan. 8, 1918.

UNITED STATES PATENT OFFICE.

CLYDE T. DEAN, OF CHICAGO, ILLINOIS, ASSIGNOR TO RUDOLPH SATTLER, OF CINCINNATI, OHIO, AND LEO J. MORAND, OF COVINGTON, KENTUCKY.

INK-SAVING ATTACHMENT FOR EMBOSsing-PRESSES.

1,252,409.

Specification of Letters Patent.

Patented Jan. 8, 1918.

Application filed March 25, 1915. Serial No. 16,927.

To all whom it may concern:

Be it known that I, CLYDE T. DEAN, a citizen of the United States, residing at Chicago, in the county of Cook and State of Illinois, have invented certain new and useful Improvements in Ink-Saving Attachments for Embossing Presses, of which the following is a specification.

The present invention relates to an ink saving attachment for embossing presses of that general character in which the surplus ink is wiped from the surface of the die by a strip of paper, and has for its object to provide a device of this character which embodies novel features of construction whereby the ink can be recovered from the paper die wiping strip and the waste thereof avoided.

Further objects of the invention are to provide a device of this character which is comparatively simple and inexpensive in its construction, which can be readily applied to an embossing press without interfering in any manner with the operation thereof, which effectively softens and recovers the ink from the paper strip or web, and which will accommodate itself automatically to either thick or thin deposits of ink upon the paper strip.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a longitudinal sectional view through the rear end of an embossing press provided with an ink saving attachment constructed in accordance with the invention.

Fig. 2 is a rear elevation of the same with the waste roller removed.

Fig. 3 is a fragmentary sectional view through the forward end of the embossing press, showing the die in a diagrammatic manner.

Corresponding and like parts are referred to in the following description and indicated in all the views of the drawing by the same reference characters.

For the purpose of illustration the ink saving attachment is shown as applied to

a conventional construction of embossing press. The reference character A designates the main frame of the embossing press, the forward portion of the press being broken away and removed, since it forms no part of and has no direct relation to the invention. The paper web 1 which constitutes the wiping strip for the steel die or plate is unwound from a feed roll 2 at the rear end of the machine and finally wound upon a waste roll 3 which is also arranged at the rear end of the machine and is disposed under the feed roll 2. From the feed roll 2 the die wiping strip 1 passes under a steel roller 4 and over a steel roller 5 to the front of the embossing press. Suitable means for making an impression, such as the die 50 (see Fig. 3), is arranged at the front of the embossing press. A link 51 is connected in the usual manner to the die or printing surface 50 for moving the same, ink being adapted to be spread over the entire surface of the die so that it will fill the depressions formed by the engraving, such depressions being indicated at 52. The ink is removed from the smooth face of the die by the wiping strip 1, leaving the ink in the depressions 52 to make an impression during the printing operation. The wiping strip 1 passes around a guide roller 53 at the front of the machine and is then carried under a pad 54 provided with a tightly stretched surface of suitable fabric 55. As the die 50 passes under the pad 54 the upper surface of the die and the lower surface of the wiping strip 1 are tightly pressed together, with the result that all of the ink on the plain surface of the die is wiped off onto the paper web 1. The conventional mechanism may be provided for bringing a fresh portion of the wiping strip 1 in operative position across the face of the pad 54 each time the die 50 is to be wiped. After having been used to wipe the surplus ink from the steel die, the paper strip 1 passes rearwardly between a pair of steel rollers 6 and 7 and over a transverse guide rod 8 to the waste roll 3. A considerable amount of ink is removed from the die plate by this ink wiping strip 1, and this ink is ordinarily wasted. The ink saving attachment includes a roller 9 of some absorbent material such as felt which supplies some suitable absorbent such as benzin from a trough 10 to the surface of the roller 7. The lower portion of the roller 110

9 runs in the liquid solvent 11 with which the trough 10 is partially filled so that as the rollers revolve the benzin will be fed continuously to the roller 7 over which the die wiping strip 1 passes. A sufficient amount of the benzin or other solvent is thus supplied to the inky side of the wiping paper to soften the ink so that it can be removed from the paper without difficulty.

10 The benzin or other liquid solvent 11 is supplied to the trough 10 through a small pipe 12 from a suitable reservoir 13.

Arranged above the return portion of the die wiping strip 1 is a suitable pad against 15 which the strip is forced by a spring actuated scraping blade 14. The pad includes a transverse bar 15 which extends across the frame A of the embossing press and is secured thereto at its extremities by suitable 20 fastening means such as the bolts 16. Arranged above the bar 15 is a rod 17 which has the ends thereof journaled within bearings 18 projecting from the bar. A set screw 19 is threaded in one of the bearings 18 for 25 engagement with the rod 17 to hold the same normally against movement. Projecting laterally from one side of the rod 17 is a series of prongs 20 which engage one end of a strip 21 of felt or similar material, the said 30 felt strip having the opposite end thereof carried under the bar 15 and secured to one edge thereof by means of a clamping bar 22. Suitable means such as the screws 23 may be provided for holding the clamping bar in 35 position and tightening or loosening the same. Any slack in the felt strip 21 can be readily taken up by loosening the set screw 19 and rotating the rod 17.

The yieldably mounted scraping blade 14 40 is carried by a slide 24 which has opposite ends thereof mounted within guides 25 secured to the sides of the main frame A of the embossing press. Coil springs 26 are arranged within the guides 25 and interposed 45 between the ends of the slide 24 and blocks 26, said blocks being engaged by adjusting screws 27 which are threaded within end pieces 28 applied to the guides. The scraping blade 14 is thus held yieldingly in engagement with the return portion of the die wiping strip 1 so as to force the latter against the before mentioned pad upon the opposite side of the paper strip. The tension of the springs 25 can be adjusted to 55 regulate the pressure of the scraping blade against the paper strip, as may be found necessary to produce the best results.

The ink upon the paper strip having been 60 previously softened by the benzin or other solvent received from the roller 7, it will be readily separated from the paper strip 1 by the scraping blade 14 and will drop therefrom upon an inclined plate or chute 29 from which it will run into a suitable cup 65 or receptacle 30.

The trough 10 for containing the solvent 11 may be supported in any suitable manner as by means of the bracket arms applied to opposite ends thereof and secured to the main frame A of the embossing machine. 70 The inclined plate or chute 29 is mounted upon and secured to a transverse bar 32 connecting the suspending arms 31, while the cup or receptacle 30 may rest removably upon a pan or flanged plate 33 projecting rearwardly from the trough 10 and secured thereto. Such a construction admits of the ink saving attachment being readily mounted upon the conventional construction of embossing press without necessitating any 80 material changes therein. The ink removed from the die plate by means of the strip of wiping paper will be first softened by applying some suitable absorbent thereto and then scraped from the paper strip and collected in a cup or receptacle. The device operates automatically, requiring no attention on the part of the operator, and will recover practically all of the ink removed from the die by the wiping paper, and which 90 is ordinarily a total loss.

Having thus described the invention, what I claim as new and desire to secure by Letters Patent, is:—

1. An ink saving attachment for embossing presses, including a trough containing a solvent, rollers feeding the solvent from the trough to the ink wiping strip so as to soften the ink thereon, a yieldably mounted scraper acting upon the ink wiping strip to 100 remove the previously softened ink therefrom, and means for collecting the ink removed from the strip by the scraper.

2. An ink saving attachment for embossing presses, including a trough containing 105 a solvent, a roller around which the ink wiping strip passes, a felt roller partially submerged in the solvent of the trough and engaging the before mentioned roller so as to coöperate therewith to supply the solvent to the ink 110 wiping strip so as to soften the ink thereon, and a scraper engaging the ink wiping strip to remove the previously softened ink therefrom.

3. An ink saving attachment for embossing presses, including a pad arranged upon one side of the ink wiping strip, a slidably mounted scraper blade arranged upon the opposite side of the ink wiping strip, a spring forcing the scraper blade into engagement with the strip and causing it to coöperate with the pad to scrape the ink from the strip, and means for collecting the ink thus recovered from the strip.

4. An ink saving attachment for embossing presses, including means for supplying a solvent to the ink wiping strip so as to soften the ink thereon, a pad arranged upon one side of the ink wiping strip, a yieldably mounted scraper blade arranged upon the 130

opposite side of the ink wiping strip and co-operating with the pad to remove the previously softened ink from the strip, and means for collecting the ink removed by the 5 scraping blade.

5. An ink saving attachment for embossing presses, including means for supplying a solvent to the ink wiping strip so as to soften the ink thereon, a pad arranged upon 10 one side of the ink wiping strip, a transversely disposed slide arranged upon the opposite side of the ink wiping strip, guides within which the ends of the slide operate, springs arranged within the guides and engaging the slide, a scraping blade carried by the slide and held in a yielding engagement with the ink wiping strip so as to co-operate with the pad to remove the previously softened ink therefrom, and means 15 for collecting the ink recovered by the scraping blade.

6. An ink saving attachment for embossing presses, including a transverse bar arranged upon one side of the ink wiping strip, 20 a felt strip extending across the face of the transverse bar, means for drawing the felt strip tightly across the face of the transverse bar, a yieldably mounted scraping blade arranged upon the opposite side of 25 the ink wiping strip and co-operating with the transverse bar to recover the ink from the strip, and means for collecting the ink removed from the strip by the scraping blade.

30 7. An ink saving attachment for embossing presses, including a transverse bar arranged upon one side of the ink wiping strip, a strip of felt extending across the face of the transverse bar, means for securing one 35 end of the felt strip to the transverse bar, a rod journaled upon the transverse bar and engaging the opposite end of the felt strip so that by rotating the rod the felt strip can be drawn tightly against the face of the 40 transverse bar, and a yieldably mounted scraping blade arranged upon the opposite side of the ink wiping strip so as to co-operate 45 with the transverse bar to scrape the ink from the strip, and means for collecting 50 the ink recovered from the strip by the scraper.

8. An ink saving attachment for embossing presses, including a trough adapted to contain a solvent, bracket arms supporting 55 the trough and secured to the frame of the embossing press, a felt roller partially submerged in the trough and engaging one of the guide rollers of the embossing press so as to co-operate therewith to feed solvent 60 from the trough to the ink wiping strip, a pad arranged upon one side of the ink wiping strip, a scraper co-operating with the pad to remove the previously softened ink from the ink wiping strip, an inclined plate 65 arranged under the scraper and mounted

upon the before mentioned bracket arms, and a receptacle receiving the recovered ink from the said inclined plate.

9. An ink saving attachment for embossing presses, including a trough adapted to 70 contain a solvent, supporting arms engaging the trough and secured to the frame of the embossing press, a felt roller partially submerged in the trough and engaging one of the guide rollers of the embossing press so 75 as to co-operate therewith to feed the solvent from the trough to the ink wiping strip, a pad arranged upon one side of the ink wiping strip, a scraping blade arranged upon the opposite side of the ink wiping strip 80 and co-operating with the pad to scrape the ink from the strip, a transverse bar connecting the supporting arms, an inclined plate mounted upon the transverse bar and arranged under the scraping blade to receive 85 the ink removed thereby from the ink wiping strip, and a receptacle for receiving the ink from the inclined plate.

10. An ink saving attachment for embossing presses, including a trough adapted to 90 receive a solvent, supporting arms engaging the trough and secured to the main frame of the embossing press, a felt roller partially submerged in the trough and engaging one of the guide rollers of the embossing press 95 so as to co-operate therewith to feed solvent from the trough to the ink wiping strip, a pad arranged upon one side of the ink wiping strip, a scraping blade arranged upon the opposite side of the ink wiping strip and 100 co-operating with the pad to remove the ink from the strip, a transverse bar connecting the supporting arms, an inclined plate applied to the transverse bar so as to receive the ink removed by the scraping blade from 105 the ink wiping strip, a plate projecting from the trough and secured thereto, and a receptacle mounted upon the plate to receive the ink from the inclined plate.

11. An ink saving attachment for embossing presses, including a trough adapted to 110 contain a solvent, a solvent reservoir, a feed pipe leading from the solvent reservoir to the trough, a felt roller partially submerged in the trough and engaging one of the guide 115 rollers of the embossing press so as to co-operate therewith to feed solvent to the ink wiping strip, a pad arranged upon one side of the ink wiping strip, a yieldably mounted scraping blade arranged upon the opposite 120 side of the ink wiping strip for co-operation with the pad to remove the previously softened ink from the ink wiping strip, and means for collecting the ink recovered by the scraping blade.

12. An ink saving attachment for embossing presses, including a trough adapted to contain a solvent, supporting arms engaging opposite ends of the trough and secured to the main frame of the embossing press, 130

- a solvent reservoir, a supply pipe leading from the solvent reservoir to the trough, a felt roller partially submerged in the trough and coöperating with one of the guide rollers of the embossing press to feed solvent from the trough to the ink wiping strip, a pad arranged upon one side of the ink wiping strip, a yieldably mounted scraping blade arranged upon the opposite side of the
- 5 ink wiping strip and coöperating with the pad to scrape the ink from the strip, a transverse bar connecting the supporting arms, an inclined plate mounted upon the transverse bar, a supporting plate projecting laterally from one side of the solvent trough, and a receptacle arranged upon the supporting plate to receive the recovered ink from the inclined plate.
- 10 13. An ink saving attachment for embossing presses, including a trough adapted to contain a solvent, supporting means detachably secured to the frame for holding the trough in position, a distributing roller partly submerged in the trough and engaging one of the guide rollers of the embossing press so as to coöperate therewith to feed solvent from the trough to the ink wiping strip, a pad arranged upon one side of the ink wiping strip, a scraper arranged
- 15 30 upon the opposite side of the ink wiping strip and coöperating with the pad to remove the previously softened ink from the ink wiping strip, and means for collecting the ink recovered from the strip by the
- 35 scraper.

14. An ink saving attachment for embossing presses including a yieldably supported slideable scraper having an edge portion disposed on the lower side of the ink wiping strip for removing ink therefrom, means for limiting the upward movement of the scraper, and means disposed beneath the scraper for collecting ink removed from the strip.

15. An ink saving attachment for embossing presses, comprising a solvent applying means for supplying a solvent to the ink wiping strip to soften the ink thereon, a yieldable scraper disposed tangentially to the strip and engaging the same for removing the softened ink therefrom, and means for collecting the ink removed from the scraper.

16. An ink saving attachment for embossing presses, comprising a solvent applying means for supplying a solvent to the ink wiping strip to soften the ink thereon, a yieldable scraper disposed tangentially to the strip and engaging the same for removing the softened ink therefrom, means for collecting the ink removed from the scraper, and adjustable means for varying the tension of the scraper.

In testimony whereof I affix my signature in presence of two witnesses.

CLYDE T. DEAN.
